UNITED STATES PATENT OFFICE.

THOMAS S. PATTERSON, OF ROSEMONT, PENNSYLVANIA.

DELIVERY-RECEPTACLE FOR POWDERED MATERIALS.

No. 909,657.

Specification of Letters Patent.

Patented Jan. 12, 1909.

Application filed January 7, 1908. Serial No. 409,637.

To all whom it may concern:

Be it known that I, THOMAS S. PATTERSON, a subject of the King of Great Britain and Ireland, residing in Rosemont, Pennsylvania, have invented certain Improvements in Delivery-Receptacles for Powdered Materials, of which the following is a specification.

My invention relates to certain improvements in devices for delivering powdered material, such as soap and other toilet preparations and granular material in general.

The main object of my invention is to so construct such a receptacle that the soap or other material will be delivered to the hand that operates the valve; and a further object is to improve the details of construction as fully described hereafter.

Referring to the accompanying drawing: Figure 1, is a vertical sectional view of my improved receptacle for soap or other granular or powdered material; Fig. 2, is a sectional plan view on the line 2—2, Fig. 1; Fig. 3, is a detached plan view of the disk mounted under the bottom plate; Fig. 4, is a detached plan view of the valve situated between the disk and the bottom plate; and Fig. 5, is a detached plan view of the stirrer.

A is the bottom plate of the receptacle having a flange a and mounted upon this bottom plate is a tubular section B of glass, forming the container for receiving the soap or other material. This tubular section of glass is inclosed in a metallic casing C, in the present instance secured to a downwardly extending flange a' of the bottom plate A and has at its upper end an internal flange c extending over the upper edge of the tubular section B. Said flange is turned down as at c' acting to hold the tubular section B central and at the same time forming a shield to prevent any soap, during the filling operation, passing between the glass section B and the protecting casing C. This casing is perforated in any suitable manner so that the amount of soap in the container is always visible; the lower row of perforations being on a line with the bottom plate so as to carry off any water which may gain access to the space between the casing and the container.

C' is a cap fitting tightly upon the casing C and the flange of this cap may have a snug fit on the casing or may be attached thereto by any suitable means.

The bottom plate A has two concentric slots a^2 therein of any desired length, through which the material may pass, and mounted on a sleeve E secured to the flanged portion a^3 of the bottom plate is a disk E' having a hole e for the discharge of material. The disk E is firmly attached to the bottom plate A and is spaced a given distance therefrom, and mounted between the disk and the bottom plate is a rotary valve I having ports i to receive material which passes through the openings a^2 in the bottom plate and deliver material to the opening e in the disk E'. The valve can be of any thickness and the holes of any size desired according to the amount of material it is desired to discharge at one time from the container.

The valve I is attached to the handhold I² through the funnel shaped section I' which has a flange i' secured to projections i^2 on the valve by soldering, brazing, or other means, so that the valve practically forms part of and must turn with the handhold I². The handhold has an opening i^3 for the discharge of material escaping from the ports of the valve.

It will be noticed that by forming the projections i^2 on the valve I cavities h are produced between the valve and the flange i' , the valve being tapered at h' . The object of tapering the valve and forming the cavities is to allow any soap or other material which finds its way between the valve and the bottom plate to escape through the openings, thus preventing clogging of the valve. The soap or other material escapes through the openings h and passes down the funnel section I' and out the same opening through which the measured quantity of soap passes.

Extending through the sleeve E is a stem M forked at its lower end; the two members m of the fork being secured to the handhold as shown, so as to leave a clear opening for the powdered material. On the upper end of this stem are arms m' which break up the material and allow it to freely flow into the openings in the valve.

The handhold I² is of such a size that it can be grasped in such a manner that the palm of the hand will be in position to receive the charge of soap or other material, thus dispensing with the use of two hands in obtaining material from the receptacle.

It will be noticed that the handhold is concaved on its underside so as to prevent the

palm of the hand touching the delivery opening of the spout, as in many cases the person using the soap will wish another charge and will apply the wet hand to the handhold and if the handhold was flat the wet hand would dampen the mouth of the opening and cause the soap to stick thereto and in time accumulate, but by making it in the manner shown this is entirely obviated. Furthermore it will be noticed that any water accidentally splashed upon the receptacle cannot gain access to the interior and dampen the soap, as the parts are so made that they will shed water, always keeping the receptacle dry.

My invention is especially adapted as a receptacle for powdered soap and can be secured to a washstand by any suitable bracket or attachment, and it will be understood that it can be used in the kitchen as a receptacle for salt, or it can contain other granular material without departing from my invention.

If the device is to be used as a powdered soap receptacle the cap is removed and any quantity of powdered soap is placed in the receptacle and the cap replaced. When it is desired to obtain a quantity of soap for toilet use, the handhold I^2 is grasped by the hand, the palm being directly under the opening in the handhold, and the handhold is turned to any degree desired or it can be completely rotated so as to bring the openings i in line with the discharge openings e in the disk E' , then the given amount of soap which is contained in the ports i of the valve will fall onto the palm of the hand.

If it is desired to receive more than one charge, the valve can be rotated until another of the ports i comes in line with the opening e in the disk, or it can be reciprocated so as to bring first one and then another of the ports i in line with the openings e , giving any amount of soap desired, although, under ordinary conditions, a single discharge of soap is all that is necessary.

It will be noticed, on referring to Fig. 2, that the opening e in the disk is so situated in respect to the openings a^2 in the base that a port i of the valve will be closed to the openings a^2 before it uncovers the opening e , preventing the draining of the soap receptacle by a careless adjustment.

I claim:

1. The combination in a receptacle for soap and other powdered materials, of a container, a bottom plate therefor having an opening therein, a disk under the bottom plate having a discharge opening out of line with the opening in the base plate, a rotary valve mounted between the two parts and having a port capable of communicating with the openings in said plates, a hollow rotary hand hold communicating with the

openings for the discharge of material, said handhold being fixed to said valve so that on turning the same a quantity of material will be discharged into the palm of the hand.

2. The combination of a receptacle, a horizontal plate forming a valve and rotatably mounted at the base of the receptacle, a hollow handhold rigidly fixed to and supported by the valve, there being an opening in the valve, said hand hold being concaved and having a funnel shaped structure for the reception of the material delivered from the opening of the valve to the hand hold.

3. The combination in a receptacle for soap and other granular material, of a container, a bottom plate having openings therein, a sleeve attached to the bottom plate, a disk attached to the sleeve some distance from the bottom plate, said disk having an opening therein out of line with the openings in the bottom plate, a valve mounted between the disk and the bottom plate and having ports therein arranged to align with the openings in the bottom plate or the opening in the disk, a handhold having a discharge opening, and a conical connecting member attaching the handhold to the periphery of the valve so that when the handhold is grasped and turned a given quantity of material will be discharged from the valve into the hand.

4. The combination of a container, a bottom plate having openings therein, a disk having an opening and having a fixed relation to the bottom plate, a valve mounted between the bottom plate and disk and having ports therein, openings at the periphery of the valve, a handhold connected to the valve at the periphery, and an opening in the handhold for the discharge of material.

5. The combination of a container, a bottom plate having an opening therein, a disk under the bottom plate having an opening out of line with the opening in the bottom plate, a valve mounted between the bottom plate and the disk and having a port arranged to align with either of the openings, a series of projections in the periphery of the disk, a handhold having a section secured to said projections, the handhold and the valve forming openings for the passage of material escaping between the valve and the bottom plate, said valve being beveled at the periphery, substantially as and for the purpose set forth.

6. The combination of a container, a bottom plate having an opening therein, a disk also having an opening out of line with the opening in the bottom plate and having a fixed relation to the bottom plate, a valve mounted between the disk and the bottom plate and having one or more ports, a handhold having an opening therein for the dis-

charge of material, and a conical section connecting the handhold with the periphery of the valve.

7. The combination of a container, a bottom plate having an opening therein, a disk also having an opening out of line with the opening in the bottom plate and having a fixed relation to the bottom plate, a valve mounted between the disk and the bottom plate and having one or more ports, a handhold having an opening therein for the discharge of material, a conical section connecting the handhold with the periphery of the valve, a stem attached to the handhold and passing through the valve, the disk and the bottom plate, and having one or more arms for breaking up material directly above the bottom plate.

8. The combination in a receptacle for soap or other material, of a bottom plate, a cylindrical glass container mounted on the bottom plate, a metallic casing surrounding the container and attached to the bottom plate, said casing having an internal flange overlapping the container at the upper edge, a valve for regulating the discharge of material, and a handhold connected to the valve and having an opening therein for the passage of material.

9. The combination of a bottom plate having upwardly and downwardly extending flanges, a glass cylinder mounted upon the bottom plate and forming a container, a metallic casing surrounding the glass container and having an internal flange at the

upper end overlapping the container, a disk mounted under the bottom plate, a sleeve connecting the disk with the bottom plate, a valve mounted between the disk and the bottom plate, said valve having ports and the bottom plate and disks having openings one out of line with the other, a handhold having a central opening, and a conical connecting section attached to the periphery of the valve, with a bifurcated stem attached to the handhold and passing through the sleeve and having arms situated above the bottom plate.

10. The combination in a soap receptacle, of a base having a vertical flange, a cylindrical container mounted on the base outside of the flange, said base also having a downwardly extending flange, a casing inclosing the container and secured to the downwardly extending flange of the base, a cap overlapping the casing, a valve, and a handhold, an extension of the handhold being attached to the valve, said extension passing under the downwardly projecting flange of the base, the parts being so designed that they will shed water preventing it gaining access to the interior of the receptacle.

In testimony whereof, I have signed my name to this specification, in the presence of 65 two subscribing witnesses.

THOMAS S. PATTERSON.
